INVENTOR.

UNITED STATES PATENT OFFICE.

WALTER W. CHASE, OF PROVIDENCE, RHODE ISLAND.

DESIGN FOR A PIN.

SPECIFICATION forming part of Design No. 34,856, dated July 30, 1901.

Application filed June 15, 1901. Serial No. 64,756. Term of patent 3½ years.

To all whom it may concern:

Be it known that I, WALTER W. CHASE, a citizen of the United States, residing at Providence, in the county of Providence and State 5 of Rhode Island, have invented and produced a certain new and original Design for a Pin, of which the following is a specification, reference being had therein to the accompanying drawings.

10 Figure 1 is a face view of a pin embodying my new design, and Fig. 2 a central vertical section of the same.

As shown in the drawings, the leading or material feature of my design consists of a 15 globular central portion *a*. Extending on either side of the said central portion *a* to

complete the pin-body are wings *b*, having a flat contour. The pin-tongue *c* and catch *d* are respectively inwardly-folded extensions of the two wings *b*. 20

Having thus described my invention, what I claim as new, and desire to secure by Letters Patent, is—

The design for a pin as herein shown and described. 25

In testimony whereof I have affixed my signature in presence of two witnesses.

WALTER W. CHASE.

Witnesses:

ROBERT W. THOMPSON,
HORATIO E. BELLOWES.
